UNITED STATES PATENT OFFICE.

FRIEND M. LEISURE, OF TEMPLETON, PENNSYLVANIA.

ENVELOP.

941,350.

Specification of Letters Patent. Patented Nov. 23, 1909.

Application filed September 3, 1909. Serial No. 516,067.

To all whom it may concern:

Be it known that I, FRIEND M. LEISURE, a citizen of the United States of America, residing at Templeton, in the county of Armstrong and State of Pennsylvania, have invented certain new and useful Improvements in Envelops, of which the following is a specification, reference being had therein to the accompanying drawing.

10 This invention relates to envelops, and the invention has for its object to provide an envelop with simple and effective means for positively sealing the same, thereby preventing the envelop from being surreptitiously opened or tampered with without the act being detected.

The above object is attained by providing the flaps of an envelop with slits and using a plurality of straps adapted to have the ends thereof retained in the envelop by the contents, while the other ends extend through the slits of the flaps and are adhesively coated or gummed, whereby the straps can be moistened and inserted in the envelop to adhere to the inner sides thereof.

25 My invention will be hereinafter considered in detail and then claimed, and reference will now be had to the drawing forming a part of this specification wherein there is illustrated a preferred embodiment of the invention, but it is to be understood that the envelop can be made of various sizes and shapes without departing from the spirit of the invention.

30 In the drawings: Figure 1 is a plan of a piece of paper or material adapted to be folded to form my improved envelop, Fig. 2 is a similar view of the envelop folded and sealed, Fig. 3 is an enlarged cross sectional view of the same, and, Fig. 4 is a perspective view of one of the straps of the envelop.

In the drawing 1 denotes a rectangular body provided with end flaps 2 adapted to fold upon the body, a bottom flap 3 adapted 45 to fold upon the body and the end flaps 2, and a top flap 4 adapted to fold upon the body, end flaps 2 and body flap 3 to close the envelop. The end flaps 2 and bottom flap 3 fold upon the dot and dash line 5, while the 50 top flap 4 folds upon the dot and dash line 6. It is at this line that the flap 4 is provided with a plurality of longitudinal slits

or slots 7, preferably three in number, one at each end of the flap 4 and one intermediate the ends thereof. The end flaps 2 are 55 provided with longitudinal slits or slots 8 and the bottom flap 3 with a slit or slot 9, the slits or slots 8 coöperating with the end slots 7 and the slit or slot 9 with the intermediate slot 7.

60 In connection with the envelop I use straps 10 adapted to have the lower ends thereof folded or bent, as at 11 to be engaged by the lower edge of the letter or epistle 12 placed in the envelop, while the 65 upper ends of the straps extend through the slits or slots 7 into the slits or slots 8 and 9. The ends of the straps are coated with an adhesive material or gummed, as at 13 and are adapted to be moistened and inserted 70 in the slits or slots 8 and 9 to adhere to the flaps 2 and 3. I reserve the right to gum both ends of the straps and to make the straps of a sufficient width to prevent the top flap 4 from being surreptitiously opened. 75

The envelop and the straps are made of paper, paperoid or a strong and durable material.

Having now described my invention, what I claim as new is:—

80 An envelop comprising a body, end flaps carried thereby and adapted to fold upon said body, said end flaps being provided with slits, a bottom flap adapted to fold upon said end flaps, said bottom flap being 85 provided with a slit, a top flap adapted to fold upon said end flaps and said bottom flap, said top flap at the folding line thereof being provided with a plurality of slits adapted to coöperate with the first mentioned slits, straps adapted to have their 90 ends bent and retained in said envelop by the contents thereof, said straps adapted to extend through the slits of the top flap into the slits of the end and bottom flaps, and 95 said straps having the ends thereof gummed to adhere to the inner sides of said end and bottom flaps, substantially as described.

In testimony whereof I affix my signature in the presence of two witnesses.

FRIEND M. LEISURE.

Witnesses:

GUS SLAGLE,
CHARLIE McCoy.
